Patented Dec. 30, 1919.

INVENTOR.

INVENTOR.
Frederick Myers

UNITED STATES PATENT OFFICE.

FREDERICK MYERS, OF NEW YORK, N. Y., ASSIGNOR, BY DIRECT AND MESNE ASSIGNMENTS, TO MYERS PHONOGRAPH CORPORATION, A CORPORATION OF NEW YORK.

GRAMOPHONE-CABINET COVER.

1,326,771.

Specification of Letters Patent.

Patented Dec. 30, 1919.

Application filed February 1, 1919. Serial No. 274,448.

To all whom it may concern:

Be it known that I, FREDERICK MYERS, a citizen of the United States, and a resident of New York, in the county of New York and State of New York, have invented certain new and useful Improvements in Gramophone-Cabinet Covers, of which the following is a specification.

This invention relates to improvements in gramophones, and particularly to improvements in machines of this type having the sound-reproducing and amplifying instrumentalities inclosed in a cabinet or casing used in connection therewith.

15 The principal object of the invention is to provide a cabinet cover containing an amplifier which may while the machine is in operation emit the sounds reproduced from the records at a higher altitude or plane than usual, so that the sound may be more clearly heard throughout a room or auditorium.

20 A further object is to provide means whereby a cabinet-cover containing an amplifier may be inclined upwardly while the machine is in operation, thereby delivering the sounds to greater advantage than a horn disposed in a fixed lower level plane.

25 And finally, a further object is to provide means whereby the cover may be held in a raised position, or permitted to remain upon the top of the cabinet, while the machine is in operation.

30 These and other objects are attained by the novel construction and combination of parts hereinafter described, and shown in the accompanying drawings, forming a material part of this disclosure, and in which:—

35 Fig. 1 is a fragmentary side elevational view, showing a cabinet and cover made in accordance with the invention, parts being broken away in order to disclose the interior construction.

40 Fig. 2 is a vertical section view taken on line 2—2 of Fig. 3.

Fig. 3 is a horizontal sectional view taken substantially on line 3—3 of Fig. 2.

45 Fig. 4 is another fragmentary sectional view, similar to Fig. 2, but showing the cover in a raised position, and drawn to an enlarged scale, and

50 Fig. 5 is a longitudinal sectional view showing the special elbow used in convey-

ing the sound and for supporting the cover when in a raised position.

Referring to the drawings, the numeral 10 designates the casing of the instrument, which may be of any preferred shape and size, and ornamented as desired, it being 60 preferably arranged to contain the records in such manner that the same are readily accessible.

The gramophone driving mechanism is contained within the upper section 11 of the 65 cabinet, through which extends a spindle 14, supporting the record table 15, the same being substantially central of the cabinet, and in all respects arranged in the usual manner.

70 Connected by hinges 16, is the cover, the same comprising a hollow base 17, preferably of rectangular cross section, and being shown as having, substantially central in its height, a transverse partition or wall 18, over 75 which is a sound chamber 19, closed at its upper side by the top 20. The front wall of the chamber 19, has a plurality of open panels 22, from which rearwardly extend the side walls 23, of the amplifier 24, which 80 may be of any suitable construction. Said side walls 23 are preferably of such contour that they curve convergently toward the rear of the amplifier, and said amplifier is shown as closed at its top by a plate 25. 85

Rigidly engaged within the amplifier in the form shown, at its converged or inner end, is an elbow 27, partially held in position by a backing or filler 28, one of elbow 90 openings facing outwardly in the direction of the amplifier axis, while the opposite end of the elbow is secured within the partition 18, through which it slightly projects, this elbow being shown as of the type known as goose-neck.

95 A bracket 30 is fixed upon the main cover plate of the casing 11 in the form shown, and has secured therein a tube 31, engaged in a sleeve-like element 32, from which the tone arm 33 extends radially in a normally 100 horizontal plane, the sound box being carried upon the extremity of the tone arm, which is movable upon the tube 31.

The extreme upper end of the tube 31 is shown as slightly beveled at its upper end 105 and adapted to engage within the lower opening of the elbow 27, when the cover is in closed position. However, when it is

desired to use the gramophone with the cover in a raised position, the cover is turned up upon its hinges 16, and a tubular support 36, having one opening 37, directed 5 downward, and another diagonally facing opening 38 directed upward, is engaged at its end 37 with the beveled end of the tube 31, while the opposite, diagonally facing end may be easily engaged within the open 10 lower end of the elbow 27, and due to its hollow construction, the sound from the tone arm is conducted to the amplifier 24, in a manner which will be clearly apparent, and besides conducting the sound, the elbow 15 constitutes an effective support for maintaining the cover in raised position, as is best shown in Figs. 1 and 4 of the drawings.

From the foregoing it will be seen that a pleasing and effective form of cabinet 20 cover has been disclosed, which permits playing of the instrument while the cover is either in raised or lowered position and in such manner as to give forth the whole 25 volume of sound, whereby the tone of the instrument is improved.

Having thus described my invention, and set forth the manner of its construction and use, what I claim as new, and desire to secure by Letters Patent, is:—

30 1. In a talking machine, in combination with a casing carrying sound-reproducing instrumentalities, a cover movable with respect to said casing, sound amplifying means carried by said cover and provided with an 35 inlet adapted to communicate with said sound-reproducing instrumentalities in the closed position of said cover, and a rigid detachable tube adapted to be interposed and form a means of communication between 40 said sound-reproducing instrumentalities and said inlet when the cover is open.

45 2. In a talking machine, in combination with a casing carrying sound-reproducing instrumentalities, a cover movable with respect to said casing, sound amplifying means carried by said cover and provided with an inlet adapted to communicate with said sound-reproducing instrumentalities in the closed position of said cover, and a tube 50 adapted to be interposed and form a means of communication between said sound-reproducing instrumentalities and said inlet when the cover is in an open position, said tube in said last-named position constituting a 55 means for retaining the cover in said open position.

60 3. In a talking machine, in combination with a casing having sound-reproducing instrumentalities, a cover hinged to said casing, sound amplifying means carried by said cover and provided with an inlet adapt-

ed when the cover is in closed position to communicate with said sound-reproducing instrumentalities within the inclosure of the casing walls, and a rigid tube adapted to be 65 interposed and form a means of communication between said sound-reproducing instrumentalities and said inlet when the cover is open.

4. In a talking machine, in combination 70 with a casing having sound-reproducing instrumentalities, a cover hinged to said casing, sound amplifying means carried by said cover and provided with an inlet adapted when the cover is in closed position to communicate with said sound-reproducing instrumentalities within the inclosure of the casing walls, and a tube adapted to be interposed and form a means of communication 75 between said sound reproducing instrumentalities and said inlet when the cover is open, said tube constituting a means for retaining the cover in open position.

5. In a talking machine, in combination 80 with a casing carrying sound-reproducing instrumentalities, a cover movable with respect to said casing, sound amplifying means carried by said cover and provided with an inlet adapted to communicate with said sound-reproducing instrumentalities in the 85 closed position of said cover, and a rigid reversely bent tube adapted to be interposed between said sound-reproducing instrumentalities and said inlet in the open position of said cover.

95 6. In a talking machine, in combination with a casing carrying sound-reproducing instrumentalities, a cover movable with respect to said casing, sound amplifying means carried by said cover and provided with an 100 inlet at the under side of said cover, said inlet adapted to communicate with said sound-reproducing instrumentalities in the closed position of said cover, and rigid means adapted to be interposed between said sound-reproducing instrumentalities and said inlet to form a means of communication therebetween in the open position of said cover.

105 7. In a talking machine, in combination with a casing carrying sound-reproducing instrumentalities, a cover hinged to said casing, sound amplifying means carried by said cover and provided with an inlet adapted to communicate with said sound-reproducing instrumentalities when the cover is in closed 110 position, and a detachable tube adapted to be interposed between said sound-reproducing instrumentalities and said inlet and support said cover in an open position.

115 In testimony whereof I have signed my 120 name to this specification.

FREDERICK MYERS.
